THERAPY X-RAY SYSTEM

Robert L. Wright, North Linthicum Heights, and
 Martin E. Hayes, Anne Arundel County, Md.,
 assignors to Westinghouse Electric Corporation,
 East Pittsburgh, Pa., a corporation of
 Pennsylvania

Application September 7, 1950, Serial No. 183,578

6 Claims. (Cl. 250—95)

1

The present invention relates to X-ray systems and particularly to such systems used for the administration of therapy treatments.

An X-ray therapy system necessarily operates at relatively high voltages ranging from two hundred to several hundred kilovolts applied to the X-ray tube, so that the generated X-ray beam has the desired penetrative value to reach deep-seated growths within the body of a patient. It has long been recognized in the art that the full operating voltage cannot be immediately applied to a therapy X-ray tube without danger of destroying the tube. Accordingly, it is desirable to gradually apply the voltage to the X-ray tube. Prior to the present invention, the voltage has been increased by manually moving a large rheostat from a high value to zero, thus increasing the voltage applied to the primary of the high voltage transformer with an attendant increase in the kilovoltage applied to the therapy X-ray tube. Such method is unsatisfactory because it is difficult for the operator to do and results in a variable time of voltage application.

A still further method utilized, and which eliminates the above noted disadvantages, is to employ several steps of resistance in series and to short-out sections of this resistance with either switches or relays operated by time delay cams. However, this latter arrangement is subject to the disadvantages that the switches too frequently stick and the relay contacts are burned and shortly destroyed by the arc formed at their separation. Moreover, the voltage is increased in jumps rather than at a smooth rate.

It is accordingly the object of the present invention to provide a therapy X-ray system in which the voltage is automatically and gradually applied to the X-ray tube in a smooth manner.

Another object of the present invention is the provision of a therapy X-ray system which is electronically controlled to cause a gradual and smooth application of the voltage to the X-ray tube.

Still further objects of the present invention will become obvious to those skilled in the art by reference to the accompanying drawing wherein:

Fig. 1 is a diagrammatic illustration of a therapy X-ray system constructed in accordance with the present invention;

Fig. 2 is a graphic illustration of the biasing voltage applied to the control grid of the electronic tube employed in the system of Fig. 1 and wherein the abscissa represents time in seconds and the ordinate biasing voltage;

Fig. 3 is a graphic illustration showing the

2

curve of the D. C. current applied to the reactor which forms a part of the system of Fig. 1 and wherein the abscissa again represents time in seconds and the ordinate D. C. current;

5 Fig. 4 is a graphic illustration showing the curve of the kilovoltage as applied to the X-ray tube of Fig. 1 and wherein the abscissa represents time in seconds and the ordinate kilovoltage.

Referring now to the drawing in detail, the 10 system as shown in Fig. 1 comprises an X-ray tube 5 connected through the customary therapy energizing circuit including a full-wave rectifying and high-voltage condenser bank arrangement 6, to the high voltage secondary winding 7 of a 15 transformer 8. The rectifying arrangement 6, however, may be of the well known half-wave Villard or Grenacher type, if desired. The primary winding 9 of the transformer 8 is connected through the A. C. windings 10 of a saturable reactor 12, to adjustable voltage-regulating taps 13 and 14 of an auto-transformer 15, upon closure of normally open contacts 16 of a relay 17. This relay 17 receives energy from appropriate voltage taps on the auto-transformer 15 upon operation 20 of a timer 18 when the "X-ray on" switch 19 is closed by a technician. The auto-transformer 15 receives its energy from a source L1-L2 of the customary commercial potential of 115-230 volts.

The D. C. winding 20 of the saturable reactor 12 is connected to a direct current source B+ and B- of approximately 300-400 volts, upon an electron discharge tube 22 becoming conductive by operation of its control grid 23. Prior to energization of the X-ray tube 5, this control grid 23 is normally biased by a voltage of approximately -50 volts from a D. C. supply source C- through normally closed contacts 24 of relay 17, with the positive terminal of this latter source being grounded in the same manner as one side 35 of the D. C. source B-, and hence both such D. C. sources are connected to the cathode 25 of electron discharge tube 22 by the ground connection G1. Connected between the grid 23 and cathode 25 in parallel with each other is a resistance 26 40 and capacitance 27 for a purpose to be herein-after described.

The system as above described operates in the following manner: upon the closure of suitable switches (not shown) to make the two D. C. supply sources and the source L1-L2 effective, a negative bias of approximately -50 volts with respect to the cathode 25 is applied to the grid 23 of the electron discharge tube 22 because contacts 24 are normally closed. Such biasing voltage is sufficiently high that no current at this

time will flow through the tube 22 nor D. C. winding 20 of saturable reactor 12. This same voltage, however, charges capacitance 27 to the full 50 volts of the D. C. supply source C— and the system is ready for operation. The technician then sets the timer 18 for the desired period of treatment and closes the "X-ray on" switch 19. Closure of this switch immediately energizes relay 17 causing it to open its normally closed contacts 24 and to close the normally open contacts 16.

Naturally, the opening of the normally closed contacts 24 disconnects the grid 23 of electron discharge tube 22 from the -50 volt source of supply C—. However, the biasing voltage applied to the grid 23 is not immediately altered, since a biasing voltage of -50 volts is still applied to the grid 23 by capacitance 27. This may be appreciated from the graphic illustration of Fig. 2. Prior to operation of the "X-ray on" switch 19, the -50 volts supplied to the grid 23 of the tube 22 from the source C— is represented by the straight horizontal portion of the curve of Fig. 2. However, upon closure of switch 19 and opening of relay contacts 24 which corresponds to "zero time," a voltage of -50 volts is still momentarily applied to the grid 23 by capacitance 27, as above mentioned. The capacitance 27 immediately begins to discharge through the resistance 26 with the rate of such discharge being determined by the value of the resistance 26. The latter is so selected that at the expiration of about six seconds, as shown by the curve of Fig. 2, the biasing voltage applied to the grid 23 will have decreased from the -50 volts to about -17 volts which is the voltage at which tube 22 becomes fully conductive. Thus there is an automatic and gradually smooth decrease in the biasing voltage applied to the grid 23.

It will also be appreciated that upon operation of relay 17 with attendant closure of normally open contacts 16, a voltage will be supplied to the primary winding 9 of high voltage transformer 8, at a value determined by the setting of the adjustable contacts 13 and 14, which passes through the A. C. windings 10 of the saturable reactor 12. At the instant of closure of contacts 16 (or "zero time" as shown in Fig. 2) the grid 23 of the electron discharge tube 22 will, as above noted, still receive its maximum biasing voltage of -50 volts which precludes the flow of D. C. current from the source of supply B+ and B— through the D. C. winding 20 of the saturable reactor 12. As a consequence, the saturable reactor has a high impedance at the instant of closing switch 19 with attendant closure of relay contacts 16, so that the kilovoltage supplied to X-ray tube 5 by the secondary winding 7 is still at low value at "zero time" as can be seen from the graphic illustration of Fig. 4.

However, as the biasing voltage applied to the grid 23 decreases, as shown in Fig. 2, the flow of D. C. current through D. C. winding 20 of saturable reactor 12 from the supply source B+ and B— will increase in the manner shown in Fig. 3 so that upon the grid 23 reaching the potential of the cathode 25 of about -17 volts in about six seconds, the D. C. current will thereafter remain constant as shown in Fig. 3. Simultaneously with such rise in D. C. current through D. C. winding 20 the impedance of the saturable reactor 12 is reduced, so that the voltage applied to the primary winding 9 and hence to the high tension secondary winding 7 is increased from low starting value at "zero time" to the maximum kilovoltage desired and as set by the adjustable con-

tacts 13 and 14, following the curve of Fig. 4.

It will thus become obvious to those skilled in the art that a therapy X-ray system is herein provided which is entirely automatic in its operation of gradually and smoothly applying the full voltage to a therapy X-ray tube thus eliminating the human element formerly utilized together with a variance in the time delay between energization of the tube and the application of full kilovoltage thereto.

Although one specific embodiment of the present invention has been shown and described, it is to be understood that still further modifications thereof may be made without departing from the spirit and scope of the appended claims.

We claim:

1. A therapy X-ray system for gradually and smoothly applying full voltage to the tube comprising a therapy X-ray tube, a circuit for energizing said X-ray tube embodying a reactor provided with a saturable magnetic core and initially having a high impedance to decrease the voltage supplied to said X-ray tube, a saturating winding on said core, an electron discharge tube provided with a control electrode and operable when conducting to supply direct current to said saturating winding to decrease the impedance of said reactor, a circuit for supplying a biasing potential to the control electrode of said electron discharge tube to render the latter initially non-conductive and including energy storage means in shunt with said control electrode, and switching means operable to simultaneously cause closure of the energizing circuit for said X-ray tube and opening of the biasing circuit for said control electrode with an attendant momentary continued application of a biasing potential to said control electrode from said energy storage means which biasing potential gradually and smoothly decreases as the energy from said storage means dissipates, thereby rendering said electron discharge tube conductive with an accompanying flow of current to said saturating winding and causing a simultaneous decrease in the impedance of said reactor with an attendant gradual and smooth increase in the voltage supplied to said X-ray tube.

2. A therapy X-ray system for gradually and smoothly applying full voltage to the tube comprising a therapy X-ray tube, an excitation circuit for said X-ray tube including a high tension transformer having its secondary winding connected through a rectifying arrangement to said X-ray tube for supplying unidirectional current to the latter, inductive means connected to the primary winding of said high tension transformer and initially having a high impedance to decrease the voltage supplied by the secondary winding to said X-ray tube and operable upon the application of a unidirectional component thereto to decrease its impedance with an attendant increase in the voltage supplied to said X-ray tube, an electron discharge tube provided with a control electrode and operable when conductive to supply a unidirectional current component to said inductive means, a circuit for supplying a biasing potential to the control electrode of said electron discharge tube to render the latter initially non-conductive and including energy storage means in shunt with said control electrode, and switching means operable to simultaneously cause operation of said excitation circuit with energization of said X-ray tube and interruption of said biasing circuit for said control electrode with an attendant momentary continued application of a biasing potential to said control elec-

trode from said energy storage means which biasing potential gradually and smoothly decreases as the energy from said storage means dissipates thereby rendering said electron discharge tube conductive to cause a decrease in the impedance of said inductive means accompanied by a gradual and smooth increase in the voltage supplied to said X-ray tube.

3. A therapy X-ray system for gradually and smoothly applying full voltage to the tube comprising a therapy X-ray tube, an excitation circuit for said X-ray tube including a high tension transformer having its secondary winding connected through a rectifying arrangement to said X-ray tube for supplying unidirectional current to the latter, inductive means connected to the primary winding of said high tension transformer and initially having a high impedance to decrease the voltage supplied by the secondary winding to said X-ray tube and operable upon the imposition of a unidirectional current component thereto to decrease its impedance with an attendant increase in the voltage supplied to said X-ray tube, an electron discharge tube provided with a control electrode and operable when conductive to supply a unidirectional current component to said inductive means, a circuit for supplying a biasing potential to the control electrode of said electron discharge tube to render the latter initially non-conductive and including energy storage means in shunt with said control electrode, a relay operable upon energization thereof to simultaneously cause operation of said excitation circuit with energization of said X-ray tube and interruption of said biasing circuit for said control electrode with an attendant momentary continued application of a biasing potential to said control electrode from said energy storage means which biasing potential gradually and smoothly decreases as the energy from said storage means dissipates thereby rendering said electron discharge tube conductive to cause a decrease in the impedance of said inductive means accompanied by a gradual and smooth increase in the voltage supplied to said X-ray tube, and timing means operable to cause energization of said relay for selected time periods.

4. A therapy X-ray system for gradually and smoothly applying full voltage to the tube comprising a therapy X-ray tube energizable from a high potential source of supply including a transformer having a primary winding, a saturable reactor provided with A. C. windings in series with the primary winding of said transformer during energization of said X-ray tube and initially having a high impedance to momentarily reduce the voltage applied to said primary winding and hence to said X-ray tube upon initial energization of the latter, a D. C. winding on said saturable reactor and operable when energized to reduce the impedance of said saturable reactor to cause an attendant increase in the voltage applied to said primary winding and hence the kilovoltage applied to said X-ray tube, a D. C. source of supply for said D. C. winding, an electron discharge tube provided with a control electrode and interposed between said D. C. winding and said D. C. supply source to cause energization of said D. C. winding upon said electron discharge tube becoming conductive, a source of biasing voltage normally applied to the control electrode of said electron discharge tube to render it initially non-conductive and to prevent energization of said D. C. winding, means including capacitance and resistance normally connected

to said source of biasing voltage and in electrical parallel with means operable to cause the energization of said therapy X-ray tube and the simultaneous disconnection of said source of biasing voltage from the control electrode of said electron discharge tube with an attendant momentary continued application of a biasing voltage to the control electrode from said means which voltage gradually and smoothly decreases to cause said electron discharge tube to become conductive with a gradually smooth rise in current through said D. C. winding and a simultaneous gradually smooth increase in the kilovoltage supplied to said therapy X-ray tube.

5. A therapy X-ray system for gradually and smoothly applying full voltage to the tube comprising a therapy X-ray tube energizable from a high potential source of supply including a transformer having a primary winding, a saturable reactor provided with A. C. windings in series with the primary winding of said transformer during energization of said X-ray tube and initially having a high impedance to momentarily reduce the voltage applied to said primary winding and hence to said X-ray tube upon initial energization of the latter, a D. C. winding on said saturable reactor and operable when energized to reduce the impedance of said saturable reactor to cause an attendant increase in the voltage applied to said primary winding and hence the kilovoltage applied to said X-ray tube, a D. C. source of supply for said D. C. winding, an electron discharge tube provided with a control electrode and interposed between said D. C. winding and said D. C. supply source to cause energization of said D. C. winding upon said electron discharge tube becoming conductive, a source of biasing voltage normally applied to the control electrode of said electron discharge tube to render it initially non-conductive and to prevent energization of said D. C. winding, means including capacitance and resistance normally connected to said source of biasing voltage and in electrical parallel with the control electrode of said electron discharge tube, a relay operable upon energization thereof to cause the energization of said therapy X-ray tube and the simultaneous disconnection of said source of biasing voltage from the control electrode of said electron discharge tube with an attendant momentary continued application of a biasing voltage to the control electrode from said means which voltage gradually and smoothly decreases to cause said electron discharge tube to become conductive with a gradually smooth rise in current through said D. C. winding and a simultaneous gradually smooth increase in the kilovoltage supplied to said therapy X-ray tube, timing means for causing energization of said relay for selected time periods, and a switch operable upon closure thereof to initiate operation of said timing means.

6. An X-ray system in which full voltage is gradually and smoothly applied to the X-ray tube, comprising an X-ray tube, a circuit for energizing said X-ray tube embodying a reactor provided with a saturable magnetic core and initially having a high impedance to limit the voltage supplied to said X-ray tube, a saturating winding on said core, an electron discharge tube provided with a control electrode and operable when conducting to supply direct current to said saturating winding to decrease the impedance of said reactor, a time constant network connected in the control electrode-cathode circuit

of said electron discharge tube such that when said network is charged, said electron discharge device is rendered non-conductive, means for charging said network, and switching means operable to substantially simultaneously cause closure of the energizing circuit for said X-ray tube and opening of the charging means for said network, whereby the biasing potential on said control electrode gradually decreases as the energy stored in said network is dissipated, thereby rendering the electron discharge tube conductive with an accompanying flow of current to said saturating winding and causing a simultaneous decrease in the impedance of said reactor
